UNITED STATES PATENT OFFICE

PATRICK J. CANNON, OF NEW YORK, N. Y.

SIDEWALK BRIDGE

Application filed December 1, 1927. Serial No. 237,050.

When erecting tall buildings it is necessary to provide a structure or bridge over the sidewalk from curb to building line to protect pedestrians from objects falling from the building during the course of construction. After the building is completed such bridges must be dismantled and removed.

The bridges used at present are of wood construction consisting of wood posts and beams nailed together and braced and provide a working floor or deck above with a separate waterproof ceiling or watershed under the deck to protect pedestrians from drippings during rainy weather. In addition a decorated apron or parapet is provided along the front over the curb which usually extends above the deck to enhance the appearance of the bridge and to prevent falling objects from rolling off the deck into the street.

Some sidewalk structures are in use which consist of hollow steel posts supporting a heavy I beam extending across the sidewalk which carries the load. This beam has to be very heavy to adequately support the load especially on long spans over wide sidewalks since the posts must be far apart. For this reason a derrick must be used to erect the structure resulting in a high cost of labor and material. Furthermore the hollow steel posts are liable to sudden collapse when bowed or bent due to excessive heat, shock or overload. This construction is not fireproof since wood is used for all the superstructure as in the all-wood bridge with its attendant disadvantages.

These bridges are not fireproof, are unsightly in appearance, difficult to erect and dismantle, are not rigid and they require a great deal of labor and time in erection. Since the bridge remains until the exterior of the building is completed, if the bridge should take fire much damage is done to the exterior of the building. Furthermore, much of the wood material, especially the watershed and apron is so damaged when dismantled that it cannot be used over again and is a total loss. Again the wood construction is necessarily fastened together with braces and wood members to obtain rigidity and in

case of accidental collapse of any one section the entire bridge is in danger.

For the above reasons and many others the present methods of constructing sidewalk bridges are unsatisfactory, uneconomical and present a menace to the safety of the public.

Therefore, it is the object of my invention to provide a sidewalk bridge which is fireproof, safe and economical.

It is a further object to provide a sidewalk bridge which can be readily erected and dismantled and provides a pleasing appearance, and in which a durable and fireproof watershed is provided which can be readily erected, dismantled and used repeatedly while the metal posts and attachments are used to support light wooden beams and decking which has been permanently fireproofed.

A still further object is to provide a removable sidewalk structure so braced and constructed to provide for all ordinary conditions met in the construction of such structures such as varying width and slope of sidewalk, positions of posts, contour of curb and building lines as well as height of decking.

The preferred form for my invention is shown by way of example in the accompanying drawings in which:

Fig. 1 is a perspective view of a sidewalk bridge embodying my invention;

Fig. 2 is a side elevation;

Fig. 3 is an enlarged side elevation of a bracket;

Fig. 4 is an end elevation of the same;

Fig. 5 is a bottom view of the same;

Fig. 6 is an elevation of a base;

Fig. 7 is a plan view thereof;

Fig. 8 is a side view of a tie-rod;

Fig. 9 is a fragmentary side view of the tie-rod fastening;

Fig. 10 is a transverse section on the line 10-10 of Fig. 8 and

Fig. 11 is a side view of a modified form of tie rod assembly.

The preferred embodiment of my invention is illustrated in the accompanying drawings and consists essentially of structural elements, in some cases of conventional or stock

material and in other instances of specially designed members.

I have shown, by way of example, a sidewalk or equivalent runway 11, having a curb edge 12. Appropriate sills 13, 13 are laid 5 on the sidewalk in spaced positions parallel to the curb 12. These sills form supports for the bases 14 of the columns, pillars or posts.

Where the posts are made from uniform 10 lengths of conventional metal I-beams, the bases take the form indicated in Figs. 6 and 7. A bottom flange 15 is adapted to rest on the sills 13 and a central portion 16 projects upwardly, being of a hollow cross-section to 15 receive the I-beam. Opposite bracing webs 17, 17 run down from the central portion 16 to the flange 15 while two other opposite webs 18, 18 extend outwardly in a common vertical plane from the central portion and flange. 20 The latter webs are apertured as at 19, to receive the connecting bolts of tie-rods as will later be described.

The posts 20 in the form of I-beams may be 25 of any suitable length and are generally made interchangeable and removably fitted to the bases 14. At their upper ends are mounted caps 21 preferably of special form as shown in Figs. 3, 4 and 5. These caps have the multiple functions of supporting the 30 superstructure, connecting with the tie-rods or braces and supporting a watershed over the passageway.

As illustrated, these caps are of metal castings with appropriate brackets for the several 35 cooperating elements. The central part consists of a lower sleeve 22 and an upper horizontal plate 23 connected by sloping sides 24. The central parts are recessed vertically at 25 to receive the upper end of the I-beam 20. The recess 25 in the upper plate has an inwardly extending edge 26 at the top against which the I-beam abuts thus supporting the casting on the upper end of the post 20. The walls 27, 27 of the lower part 22 are narrowed 40 at their centers to fit snugly against the central web of the post 20 and are also drilled at 28 so that a bolt may be passed through the walls 27, 27 and the intervening web of post 20. In like manner the horizontal plate 23 where it is centrally recessed, has spaced 45 walls 29 apertured at 30 to be bolted to the web of the post. Strengthening flanges 31, 31 extend inwardly of the sides 24, 24 and plate 23, from the lower portion 22 to the upper depending member of the plate in 50 which the end of the post is received.

The lower sleeve 22 has opposite side walls 32, 32 with outwardly extending central webs 33, 33 terminating in vertical spaced 60 cheeks 34, 34. These cheeks form inner parts of stirrups 35, 35 of appropriate proportions to receive the frame members 36. The outer parts of the stirrups are upstanding walls 37, 37. 65 The web 33 has a depending lug 38 drilled

as at 39 to receive a bolt connecting it with the end of a tie-rod.

The side walls 32, 32 are extended in opposite directions to provide parallel spaced flanges 40, 40. Suitable holes 41, 41 run 70 through these flanges to receive the bolts used in assembling the spacing members.

The upper horizontal plate 23 extends horizontally of the cap to form a platform 42, which is suitable to support a truss-member 75 43. The side walls 44, 44 of the plate 23 extend upward from the platform 42 in parallel relation on each side of the truss 43. The angles between 44 and 42 have small web connections 45, 45 serving to brace the side walls 80 44, 44 and also to engage the truss member firmly and prevent its longitudinal movement of the platform except when lifted from the latter.

The open ends of the plate 23 form lips 46, 46 having on their lower surfaces a slight recess as shown on Fig. 3 whereby clamping bars 47 may be extended and held. These bars are U-shaped and reach upward with their free ends held in cross-bars 48 by means 90 of nuts 49.

Means are provided to connect the several posts together and these means are preferably in the form of tie-rods such as indicated particularly in Figs. 1, 2, 8, 9 and 10. Since the spacing between the posts is subject to variation dependent on the dimensions of the passageway covered, it is necessary to allow for ready adjustment of the tie-rods. This has been done by making them of interconnected parts, adjustably fastened together. As illustrated, the horizontal tie-rods, 50, 50 are each of hollow or solid rod formation having one plain end 51 and one end in the form of an eye 52. These rods 50, 50 are each 100 connected by bolts through their ends 52 to the desired part of the caps 21. This may be at the lug 39 or one of the holes 41, 41 in the flanges 40. The opposite tie-rod may be similarly connected to another cap 21 or 110 a base 14 or a metal strap 53 (Fig. 1).

The overlapping free ends of the rods are brought into parallel spaced positions as shown in Figs. 8, 9 and 10, and tie-plates 54, 54 having inward flanges 55, 55 clamped tightly against the rods 50, 50 by means of the bolts 56, 56. This forms a rigid, unyielding connection stronger than the tie-rods themselves and not subject to distortion during 115 operation.

A modified form of tie-rod connection is shown in Fig. 11, where the free ends of rods 50, 50 are threaded and connected by a turn-buckle 57. This is particularly advantageous where it is desired to parallel a truss and put the same under compression, thus relieving the tie-rods of some strain.

The above described structural elements in their assembly form a supporting framework of open character yet rigid against distor- 120 125 130

tion and entirely independent as to its interconnection from the load-carrying elements. It is therefore possible to reduce the bulk and weight of the bracing members to within the limits of easily handled parts.

5 The actual load-sustaining elements consist of longitudinal girders 58, 58, bridging the posts in a direction at right angles to the truss members 43. As the girders rest directly above the posts the weight is transmitted directly without throwing any on the intermediate portions of the truss members 43.

10 Floor beams 59 rest on the girders 58, 58 and at right angles to the latter. A suitable flooring 60 is laid on the beams. The outer edge of this flooring or deck is guarded by an apron or parapet 61 formed of removable sections 62, 62, suitably bolted together and to the deck 60. This allows its installation in completed sections by manual labor as opposed to the usual mechanical hoisting of the apron as an entirety or its construction directly on the deck 60 or in place.

15 Beneath the deck, it is necessary to provide a ceiling for the passageway and preferably this should be both watertight and fireproof. I have shown a ceiling 63 formed of sections of corrugated metal laid with its ends over the frame members 36, 36. By using appropriate widths of the frame members 36, 36 sufficient inclination will be given the ceiling 63 to shed water over the curb 12. Any suitable lighting fixtures 64 or other facility may be provided in conjunction with the ceiling 63.

20 In Fig. 11, there is shown an arrangement by which the rigidity of the structure is assured in directions at right angles to the truss-members 43. The consecutive posts 20, 20 are spaced at their tops by trusses 65, the ends of which rest on the lower members 22 of the caps and abut against the webs of the posts. Adjustment of the turn-buckles 57 serve to clamp the trusses 65 and consequently the posts 20 into a firm position at the same time the members 43 connect the opposite posts 20 of the inner and outer rows. Thus the frame is rendered rigid on rectangular lines both longitudinally and laterally of the passageway.

25 It will be understood that all of the lumber used in this structure will be adequately fire-proofed thus minimizing the risk of damaging the adjacent building walls. At the same time by such fireproofing it is possible to assure the maintenance of the sidewalk bridge against collapse or damage in case it is subjected to a fire.

30 With a bridge assembled as above indicated the minimum of hoisting will be required as the posts, beams, trusses and other fittings are all within the sizes that may be manipulated by ordinary manual labor. Thus, the supporting frame of posts, is

35 topped by a short transverse truss 43 which since it does not carry a heavy load, may be made relatively light. The supporting girders 58 may likewise be relatively short by reason of the spacing of the posts longitudinally of the passageway. The other structural details are likewise easily assembled.

40 By reason of the particular arrangement of the several supporting devices, the structure is braced and anchored in both longitudinal and lateral directions without using bulky braces or disfiguring angles. The passageway and view are thus rendered clear and sightly. Due to the interchangeable character of the parts, the deck may be maintained level irrespective of irregularity or slope of the sidewalk merely by the selection of the appropriate length of posts.

45 The tie-rods 50 with the connections 54 are unusually rigid since reinforced at the center against bending. An easy adjustment for length follows obviously from this form of connection. Where the brace 65 is used, an additional reinforcement against compression is evident.

50 The use of the cap and bracket as herein developed makes possible the utilization of stock materials and variation in dimensions of the bridge itself. Also the several structural units are interconnected by the single cap bracket and tied in most rigidly. This results from the improved design given the bracket and its associated parts.

55 It will be apparent that while I have shown one preferred form which my invention may take, yet many changes in minor details and proportions may be made within the scope of the appended claims.

60 What I claim is:

1. A sidewalk bridge comprising parallel rows of vertical posts, a cap on each post, trusses extending transversely between opposite posts of the rows and longitudinal load-sustaining girders resting on the trusses above the caps.

65 2. A sidewalk bridge comprising parallel rows of vertical posts, a cap on each post, trusses extending transversely between opposite posts of the rows, tie-rods connecting adjacent caps of each row and longitudinal load-sustaining girders resting on the trusses above the caps.

70 3. A sidewalk bridge comprising parallel rows of vertical posts, a cap on each post, trusses extending transversely between opposite posts of the rows, tie-rods connecting adjacent caps of each row, compression members spacing adjacent caps of each row over the tie-rods and longitudinal load-sustaining girders resting on the trusses above the caps.

75 4. A sidewalk bridge comprising parallel rows of vertical posts, a cap on each post, trusses extending transversely between opposite posts of the rows, compression members

abutting adjacent caps of each row, tie-rods connecting adjacent caps of each row and means for contracting said tie-rods.

5. A sidewalk bridge comprising parallel rows of vertical posts, a cap on each post, trusses extending transversely between opposite posts of the rows, longitudinal girders resting on the trusses above the caps and a deck supported by said girders.

10. 6. A sidewalk bridge comprising parallel rows of vertical posts, a cap on each post, means extending transversely of the rows for bracing the posts and means extending longitudinally of the rows to sustain a load independently of the transverse bracing means.

15. 7. A sidewalk bridge comprising parallel rows of vertical posts, a cap on each post, trusses extending transversely between opposite posts of the rows, longitudinal girders 20 resting on the trusses above the caps, a deck supported by said girders and a ceiling supported by said caps.

8. A bracket cap for a post comprising a lower sleeve slidable over the post, a trans- 25 verse upper load-sustaining platform spaced from said sleeve and resting on the end of the post and a stirrup on one side of said sleeve.

9. A bracket cap for a post comprising a lower sleeve slidable over the post, a trans- 30 verse upper load-sustaining platform spaced from said sleeve and resting on the end of the post and lateral apertured extensions on said sleeve.

10. A bracket cap for a post comprising a lower sleeve slidable over the post, a trans- 35 verse upper load-sustaining platform resting on the end of the post, a U-shaped clamp and a lipped extension on said platform to hold said clamp.

40. 11. A bracket cap for a post comprising a lower sleeve having an H-shaped vertical passageway, a transverse upper platform, divergent side walls connecting the sleeve with the platform and an H-shaped recess in 45 the lower part of the platform opposite the passageway in the sleeve.

12. A bracket cap for a post comprising a lower sleeve slidable over the post, a trans- 50 verse upper load-sustaining platform resting on the end of the post, side walls connecting the platform with the sleeve in spaced relation and spaced flanges on the sleeve at right angles to the connecting side walls.

In testimony whereof, I affix my signature.

55 PATRICK J. CANNON.
